PLATE WARMER

Victor Kobler and Werner Kobler, Zurich, Switzerland, assignors to Kobler & Co., Zurich, Switzerland

Application September 14, 1950, Serial No. 184,814
In Switzerland September 22, 1949

6 Claims. (Cl. 126—261)

1

This invention relates to plate warmers comprising candle seats that are arranged in a container having a cover plate provided with passages for the candle heat to pass through.

With the plate warmers, nowadays in vogue, particularly, the lighting of the candles is often somewhat difficult, due to the candles being disposed at the bottom of a relatively deep container, so that the lighting of the candles by means of matches is hampered.

With a view to eliminating this drawback, in the plate warmer, according to the present invention, the candle seats can be raised, by means of a manually operable hoisting device, close to the passages in the cover plate, in order to improve the access to the candle seats.

By this means, the cumbersome inserting of the burning matches into the container, which may give rise to setting afire adjacent objects, is done away with. In the raised position of the candle seats, the lighting as well as the extinguishing of the candles can be easily effected even when the cover plate is set in place.

Hereinafter the object of the invention is explained, in detail, by way of example, with reference to the accompanying drawings in which

Fig. 1 shows a longitudinal section through a first example.

Fig. 2 shows a detail of Fig. 1 with the candle seats fixed in position.

Fig. 3 shows a top plan view of the plate warmer of Fig. 1 with the cover plate removed.

Fig. 4 shows a section on the line IV—IV in Fig. 1.

Fig. 5 shows a section similar to Fig. 4 with a candle seat in its raised position.

Fig. 6 shows a longitudinal section of a second example, and

Fig. 7 shows a longitudinal section through a modification of the invention in a manner similar to Fig. 2.

As shown in the drawings, the plate warmer is provided with a container 1 on the bottom of which candle seats in the form of sockets 2 surrounded by ribs 3 of annular form are arranged. In these sockets 2, candles 4 are inserted in a known manner. On an offset circumferential flange of the container 1, a removable cover plate 6 provided with one or more circular passages 5, in the form of perforations, is seated. For the reception of a dish for serving food the cover plate 6 is provided with longitudinal ribs 7, which extend on both sides of the perforations 5, approximately throughout the length of the cover plate 6.

In the example of the plate warmer, as shown in Figs. 1 to 5, the hoisting device is provided with a rocking bar 8 which is parallel to the longitudinal axis of the container 1 and mounted in the side walls of the latter. This bar projects from the container 1 at both ends thereof and

2

carries at each of said ends a turn-button 9. Instead of turn-buttons levers may be provided. The rocking bar 8 carries intermediate of its end portions two spaced swing arms 10 forming with portions of the bar two stirrups that are securely connected to the bar laterally of the longitudinal axis of the container and above the middle of the depth of the latter. The end portion of each arm 10 is bent up into a stud so that the studs on the 10 pairs of arms forming the individual stirrups point towards each other and extend parallel to the bar 8. These pairs of cooperating studs serve as pivots for supporting, by means of a bead or flange on the respective sockets 2, supporting rings 11. This construction permits of easily removing the candle sockets, for example, for cleaning purposes. One of the end portions of the bar 8 projecting out of the container 1 is surrounded by a coiled spring 12 which abuts at one 20 of its ends against the wall of the container and at the other against the turn-button 9. By means of the spring 12 the rocking bar 8 is retained in its normal axial position, i. e., in the lower or upper end position. Close to one of the 25 side walls of the container 1, to the rocking bar 8 a further swing arm 13 is connected so as to lie in the plane of the swing arms 10 of said stirrups, the end portion of said arm being bent in parallelism with the bar 8 in an outward direction relative to the container. This end portion serves for cooperation with a spring plate 14 acting as a checking device. This plate is connected at the lower end portion thereof by a screw 15 to the container 1 and supported by the 30 aforesaid inner offset of the circumferential flange of the container by means of its severally offset upper end portion, where the spring plate is secured by the closed cover plate 6.

The operation of the described plate warmer 40 is as follows. Under the assumption that the individual parts are in their positions, as shown in Fig. 1, the lighting or extinguishing of the candles 4 is eased when the rocking bar 8 is rocked, by means of one or both turn-buttons 9, 45 in such manner, that the swing arms 10 and, consequently, the candle sockets 2 are rocked upwardly into the positions shown in Figs. 2 and 5.

While this rocking movement of the candle sockets 2 toward the perforations 5 continues, 50 said end portion of the arm 13 slides over the inner side of the spring-plate 14, whereby the latter shifts towards the adjacent wall of the container.

After the candle sockets have been rocked into 55 their upper end positions, the end portion of the arm 13 engages with an offset or shoulder 16 on the spring-plate 14, thereby arresting the bar 8 from rotating. With this arrangement the upper edges of the candle sockets 2, in their upper positions, are approximately flush with the cover plate so that ample access is provided to the 60

candles 4 by way of the perforations 5 in the cover plate 6. After the candles have been lit or extinguished, whatever the case may be, the rocking bar 8 is axially shifted against the action of the spring 12 until the end portion of the arm 13 is disengaged from the offset 16 of the spring-plate 14 to such an extent that the candle sockets 2 can be rocked back into their initial positions between the ribs 3. By effect of the rotatable bearing arrangement between the supporting rings 11 on the end portions of the relevant arms 10, the axis of the candle sockets 2 remains vertical in each position of the latter.

Fig. 7 of the drawings shows a construction in which the spring plate 14 as shown, as for example, in Fig. 2 is omitted. In place of such a spring plate the inner surface of the front wall of the container is inclined inwardly so that it has substantially the same effect as the spring plate in the other embodiments.

Instead of using a spring-plate 14, an appropriate spring arm may be employed which is adapted to shift into a corresponding depression in the wall of the container. Alternatively, the spring 12 can be adapted to force the end of the arm 13 into correspondingly depressed wall portions so as to hold the rocking bar in either the lower or upper end position. Further, two or more candle sockets may be provided which can be rocked simultaneously by means of a single rocking bar 8.

Fig. 6 shows a further exemplification in which, in the same manner as explained in the example just above, two candle sockets 2 can be hoisted independently of each other by a separate rocking bar 8'. For this purpose the two rocking bars 8' can be mounted in a support 17 with their inner ends in the middle part of the container 1, a spring 12 being provided on each end of said bars 8', which ends project from the container and bear the buttons 9. Furthermore, on each rocking bar 8' an arm 13 is secured, the ends of said arms cooperating with a spring-plate 14. Otherwise, the manipulation of this plate warmer is like that of the first example.

We claim:

1. In a candle heated plate warmer, comprising candle sockets, a container surrounding said sockets, a cover plate at the top of said container, said cover plate having openings therethrough, a hoisting device, for hoisting said sockets into said openings so that the upper edge of the sockets is approximately flush with the upper side of the cover plate, a checking device for arresting the candle sockets in raised positions thereof, and at least one spring-plate provided in said checking device for cooperation with a part of the hoisting device.

2. In a candle heated plate warmer, comprising candle sockets, a container surrounding said sockets, a cover plate at the top of said container, said cover plate having openings therethrough, a hoisting device for hoisting said sockets towards said openings, and supporting rings arranged on said hoisting device, each for attaching a socket thereto so that the latter can be easily removed for cleaning purposes.

3. In a candle heated plate warmer, comprising candle sockets, a container surrounding said sockets, a cover plate at the top of said container, said cover plate having openings therethrough, a rocking bar operated hoisting device for hoisting said sockets into said openings so that the upper edge of the sockets is approximately flush with the upper side of the cover plate, at least one

rocking bar mounted in said container and provided with socket-receiving pairs of swing arms, a checking device for arresting the candle sockets in raised positions thereof, and at least one spring plate provided in said checking device for cooperation with a part of the hoisting device.

4. In a candle heated plate warmer, comprising candle sockets, a container surrounding said sockets, a cover plate at the top of said container, said cover plate having openings therethrough, a rocking bar operated hoisting device for hoisting said sockets into said openings so that the upper edge of the sockets is approximately flush with the upper side of the cover plate, a single rocking bar mounted in the ends of the container and having its ends extended out of said container, said bar through said extended ends being operable for hoisting the candle sockets simultaneously, a checking device for arresting the candle sockets in raised positions thereof, and at least one spring-plate provided in said checking device for cooperation with a part of the hoisting device.

5. In a candle heated plate warmer, the provision of two candle sockets, a container surrounding said sockets, a cover plate at the top of said container, said cover plate having openings therethrough, a rocking bar operated hoisting device, for hoisting said sockets into said openings so that the upper edge of the sockets is approximately flush with the upper side of the cover plate, two rocking bars mounted in the container and having the ends thereof extended out of said container and operable to rock said bars for hoisting said candle sockets independently of each other, a checking device for arresting the candle sockets in raised positions thereof and at least one spring-plate provided in said checking device for cooperation with a part of the hoisting device.

6. In a candle heated plate warmer, comprising candle sockets, a container surrounding said sockets, a cover plate at the top of said container, said cover plate having openings therethrough, a rocking bar operated hoisting device, for hoisting said sockets into said openings so that the upper edge of the sockets is approximately flush with the upper side of the cover plate, said rocking bar mounted in said container to permit of axial movement of said bar and provided with a socket-receiving pair of swing arms, a checking device for arresting the candle sockets in raised positions thereof, a spring acting against said rocking bar in the axial direction of the latter, and means for releasing said spring action when said checking device is to be rendered ineffective.
